UNITED STATES PATENT OFFICE.

OSCAR BERGSTROM, OF NEW YORK, N. Y.

DESIGN FOR TILING.

SPECIFICATION forming part of Design No. 36,356, dated June 9, 1903.

Application filed April 28, 1903. Serial No. 154,725. Term of patent 7 years.

To all whom it may concern:

Be it known that I, OSCAR BERGSTROM, a citizen of the United States, residing in the city of New York, Brooklyn borough, county of Kings, and State of New York, have invented a new, original, and ornamental Design for Tiling, as illustrated in the accompanying drawing.

The drawing herewith illustrates a section 10 of tiling in which my novel design is embodied, and such illustration will render the same so clear as to cause any detail description thereof unnecessary.

What I claim is—

The ornamental design for tiling substantially as herein illustrated. 15
